UNITED STATES PATENT OFFICE.

CHRISTIAN WILLIAM MEINECKE, OF JERSEY CITY, NEW JERSEY.

DESIGN FOR A POT OR JAR.

SPECIFICATION forming part of Design No. 19,762, dated April 15, 1890.

Application filed March 13, 1890. Serial No. 343,783. Term of patent 7 years.

To all whom it may concern:

Be it known that I, CHRISTIAN WILLIAM MEINECKE, a citizen of the United States, residing at Jersey City, in the county of Hudson and State of New Jersey, have invented and produced a new and original Design for Pomatum-Pots, of which the following is a specification, reference being had to the accompanying drawing, forming part of the

same.

This design has for its object to provide a novel pomatum-pot, as hereinafter described, and shown by the accompanying drawing, in which the figure is a perspective view of the

pot.

In the drawing, the letter A indicates the pot-body, polygonal in cross-section, with a

projecting base-band *b*, and surmounted by a projecting band *d* and a circular top having spiral ribs *f*.

What I claim is—

The design for a pot, consisting of the polygonal body A, having the base-band *b*, and surmounted by the band *d* and the circular top having spiral ribs *f*, substantially as shown and described.

In testimony whereof I have hereunto set my hand in the presence of two subscribing witnesses.

CHRISTIAN WILLIAM MEINECKE.
